DESIGN FOR A TRANSPARENT BOX TOE SHOE

Albert J. Cocozella, Lynn, Mass., assignor, by mesne assignments, to Harold M. Fisher,
Brookline, Mass., and said Cocozella

Application August 23, 1940, Serial No. 94,595

Term of patent 14 years

To all whom it may concern:

Be it known that I, Albert J. Cocozella, a citizen of the United States, residing at Lynn, in the county of Essex and Commonwealth of Massachusetts, have invented a new, original, and ornamental Design for Transparent Box Toe Shoes, of which the following is a specification, reference being had to the accompanying drawing forming part thereof.

The figure in the drawing is a view in perspective of a transparent box toe shoe embodying my design.

My design for a shoe as illustrated is characterized by an opening in the toe end of the upper extending substantially the full width of the toe portion and upwardly so as to include substantially the entire side walls of the toe portion, and a transparent box toe portion completely filling said opening extending upwardly and then rearwardly to the edge of the opening in the vamp and the said opening being outlined by a line of stitching in the vamp.

I claim:

The ornamental design for a transparent box toe shoe, substantially as shown and described.

ALBERT J. COCOZELLA.
